SHELTER

Allan J. Hastings, Los Angeles, Calif., assignor to The Boeing Company, Wichita, Kans., a corporation of Delaware

Filed Oct. 18, 1961, Ser. No. 67,135

Term of patent 14 years

(Cl. D13—1)

FIG. 1

FIG. 2

FIG. 3

FIG. 4

FIG. 5

FIG. 6

FIGURE 1 is a perspective view of a shelter embodying my novel design.

FIGURE 2 is a top plan view thereof.

FIGURE 3 is a side elevational view thereof.

FIGURE 4 is a perspective view of the shelter in inverted position.

FIGURE 5 is a top plan view of the inverted structure.

FIGURE 6 is a side elevational view of the inverted structure.

A characteristic of the design is the formation of a series of centrally-intersecting, diametrical straight lines of like length extending rectilinearly horizontally from edge to edge of a symmetrical shelter which is low relative to the length of said lines, each diametrical straight line being defined by the intersection of the planes of two pairs of flat triangular sections, all as shown.

I claim:

The ornamental design for a shelter, as shown and described.
